UNITED STATES PATENT OFFICE.

JAMES A. CAMERON, OF CHICAGO, ILLINOIS, ASSIGNOR TO TAPRELL, LOOMIS & COMPANY, OF CHICAGO, ILLINOIS, A CORPORATION OF ILLINOIS.

EASEL.

1,396,724.

Specification of Letters Patent. Patented Nov. 15, 1921.

Application filed August 3, 1920. Serial No. 400,967.

To all whom it may concern:

Be it known that I, JAMES A. CAMERON, a citizen of the United States, of Chicago, in the county of Cook and State of Illinois, 5 have invented certain new and useful Improvements in Easels; and I do hereby declare the following to be a full, clear, and exact description of the same, reference being had to the accompanying drawing, forming a part of this specification, and to the reference-numerals marked thereon.

My present invention relates to stationery and more particularly to photographic mounts such as are usually made of heavy 15 paper for the display of portraits and other pictures and the invention has for its object to provide a mount of the easel type that will be simple and cheap to manufacture and which will be slightly when folded to a 20 flat condition in which the picture is protected or covered, the improvements being directed in part toward effecting a safe and compact folding of the locking devices for holding the easel structure in extended position. To these and other ends the invention resides in certain improvements and combinations of parts, all as will be hereinafter 25 more fully described, the novel features being pointed out in the claims at the end of the specification.

In the drawings:

Figure 1 is a front view of a photographic mount in folded condition and constructed in accordance with and illustrating one embodiment of my invention;

Fig. 2 is a rear view of the device folded;

Fig. 3 is a rear view of the device extended to form an easel;

Fig. 4 is an enlarged horizontal section on the line 4—4 of Fig. 2;

Fig. 5 is a top view of the device extended as in Fig. 3;

Fig. 6 is a perspective view of the article in use, and

Fig. 7 is a side view.

Similar reference numerals throughout the several views indicate the same parts.

My present invention is shown embodied in a photograph mount or holder of the usual 50 type in so far as it includes a backing or body portion 1 provided with corner clips 2 in which the photograph or picture 3 is held, as shown in Fig. 6. Legs 4 are, in the present instance, formed at the lower corners of the backing and integral with the

latter are a pair of side flaps 5 hinged thereto along a scored line 6 at the lateral edges of the body of the backing. These flaps or wings act as covers and may be folded over upon each other, as shown in Fig. 1, to protect the picture when desired and to reduce the size of the mount for shipping.

The lower edges of the flaps 5 are cut at an angle of less than 90° and the flaps may be folded back to the positions shown in 65 Figs. 3, 5, 6 and 7 to support the backing and the picture mounted thereon in an upright position in which case, the angle given to the lower edges of the flaps causes the backing to be slightly rearwardly inclined, 70 as clearly shown in Fig. 7, so that it will rest securely and not have a tendency to tip over toward the front. The upper edges of the flaps are also preferably cut at the same angle, not only to make them symmetrical 75 when folded, as in Fig. 1, but so that when the picture is viewed from the front, at a usual angle of vision, the supporting flaps will not be visible or will, at least, be less prominent.

As best shown in Fig. 4, I prefer to build up the backing 1 with a reinforcing sheet 7 secured thereto only at its edges, as indicated at 8 and preferably centrally embossed or, at any rate, the two sheets are 85 slightly spaced apart to accommodate a tongue 9 the major portion of which lies between them when the mount or easel is folded, as in Fig. 2. The tongue extends through a horizontal slot 10 in the sheet 7 which it 90 closely fits with an enlargement 11 projecting to the exterior. The body of the tongue is slightly tapered toward its lower end which is provided with an enlargement 12 forming shoulders 13 preventing it from 95 being readily or inadvertently entirely removed from the backing. The material of the tongue is preferably transversely scored to make a hinge or bending point along the line 14 close to the enlargement 12. When the device is extended for use, the tongue is 100 grasped by the enlargement 11 of the finger-piece and drawn out until the shoulders 13 reach the slot and halt the withdrawing movement whereat the hinge line 14 is 105 brought coincident with the slot and allows the tongue to be bent down rearwardly to a substantially horizontal or rearwardly extending position transversely to the backing 1. Notches 15 at both ends of the enlarge- 110

ment 11 form shoulders that are engaged over the free edges of the side or supporting flaps 5 so that the tongue acts as a brace between them and holds them in a converging or supporting position as shown in Figs. 3 and 5. The tendency of the side flaps is, of course, to separate or move away from each other into the plane of the body of the backing so that the spring of the flaps holds them against the shoulders 15.

The tongue 9 is preferably connected with the backing to the slot 10 at a relatively high point so that as it swings on the hinge 14, the shoulders 15 will travel in an arc intersecting the upper free corners of the flaps 5 and in this way, as the tongue is drawn out of its slot, it rises above the flaps and is then swung down into engagement with their rear edges upon which the notched shoulders 15 jam as the movement is continued to a low point. This effectively prevents the parts from becoming easily disengaged from each other.

When it is desired to fold the device, the tongue is disengaged from the flap by a true upward swing and then thrust down into its slot 10 in a direction in the plane of the backing and the flaps 5 are folded forwardly over the face of the picture. In this condition, the tongue is not exposed and does not become readily damaged.

I claim as my invention:

1. In a picture mount or the like, the combination with a backing and lateral flaps adapted to fold into overlapping relation-

ship against the face thereof, or to be swung rearwardly to act as easel supports, of a retaining member extending rearwardly from the backing and provided with shoulders to engage and lock the flaps at their edges, said retaining member being foldable to inoperative position by an endwise bodily movement in the plane of the backing.

2. In a picture mount or the like, the combination with a backing having double walls, the rear wall being provided with a slot, and lateral flaps adapted to be swung rearwardly to act as easel supports, of a retaining member extending slidably through the slot and having a retracted position in which its major portion is accommodated between the said walls, said brace being provided with shoulders adapted to engage the flaps at their edges and lock them in supporting position.

3. In a picture mount or the like, the combination with a backing having double walls, the rear wall being provided with a slot, and lateral flaps on the backing adapted to fold against the face thereof or to be swung rearwardly to act as easel supports, of a retaining member extending slidably through the slot and having a retracted position in which its major portion is accommodated between the said walls, said brace being provided with shoulders adapted to engage the flaps at their edges and lock them in supporting position.

JAMES A. CAMERON.
